Robert D. Kahn, Rockville Centre, N.Y., assignor to
Fedtro, Inc., Rockville Center, N.Y., a corporation
of New York

Filed Dec. 2, 1968, Ser. No. 14,743

Term of patent 14 years

Int. Cl. D13—02

U.S. Cl. D26—15

FIG. 1

FIG. 2

FIG. 3

FIG. 4

FIG. 1 is a front perspective view of an auxiliary battery charger;

FIG. 2 is a rear perspective view of the battery charger, showing the cover removed from the base of the battery charger;

FIG. 3 is a right side elevational view of the base of the charger.

The stippled shading on top of the battery charger is the battery charger, the left side elevational view being a mirror-image thereof; and

FIG. 4 is a top plan view of the base of the battery intended to indicate contrasting texture.

I claim:

The ornamental design for an auxiliary battery charger, as shown and described.
